UNITED STATES PATENT OFFICE.

WILLIAM FLANAGAN AND LOUIS MONROW MULLINIX, OF LOUIN, MISSISSIPPI.

SCREEN WINDOW OR DOOR.

937,585.

Specification of Letters Patent. Patented Oct. 19, 1909.

Application filed September 1, 1908. Serial No. 451,231.

To all whom it may concern:

Be it known that we, WILLIAM FLANAGAN and LOUIS MONROW MULLINIX, citizens of the United States of America, residing at 5 Louin, in the county of Jasper and State of Mississippi, have invented new and useful Improvements in Screen Windows or Doors, of which the following is a specification.

This invention relates to screen windows 10 or doors, and one of the principal objects of the same is to provide means whereby flies from the inside of the house may escape through an orifice or opening between two members of the screen.

15 It is a well known fact that a few flies will always gain entrance to a house even if provided with screen windows and doors. These flies will seek the light and may be found upon the window and door screens. Under 20 ordinary conditions it has been necessary to raise the screen to drive these flies out, and during this operation oftentimes other flies gain an entrance to the house.

25 It is one of the principal objects of our invention to provide means whereby the flies may gain an exit and at the same time to provide means whereby flies may be caught in a trap and destroyed.

30 The objects and advantages of our invention may be attained by means of the construction illustrated in the accompanying drawing, in which,—

35 Figure 1 is a perspective view of a window screen made in accordance with our invention. Fig. 2 is a vertical section through the same.

Referring to the drawing, the numeral 1 40 designates a frame for the screen, and it will be understood that this frame may either be a door frame or a window frame. The lower screen member 2 is inclined from the bottom of the screen upwardly and outwardly from the inside, and the frame member of the screen may be made of such shape 45 as to provide for this inclination. At the top of the wire cloth screen 3 a metal binding 4 is secured, said metal binding being seated at its ends in recesses in the frame. The upper screen member 3^a is disposed vertically in the frame, and at the lower end a loop 5 is formed therein, and the terminal 50 upper edge of said wire cloth is provided with a metal binding 6 which is seated at its ends in a suitable recess in the frame. The 55 metal bindings 4 and 6 of the two screen members are spaced apart a sufficient dis-

tance to permit a fly to pass between them. The upper screen member 3 terminates at a point below the upper cross bar of the frame and is provided with a metal binding 7. A 60 fly trap 8, preferably made of wire cloth and having end caps 9, is supported in the space between the upper edge of the member 3^a and the top cross bar of the frame, said trap having its terminal ends disposed upon opposite sides of the binding 7 and spaced therefrom a sufficient distance to permit a fly to enter the trap 8. The trap 8 is supported by means of end pintles 10 on the caps 9, said pintles fitting in recesses 11 in 70 the screen frame, thus permitting the trap to be removed whenever desired to destroy the flies therein. Handles 12 are provided for removing the trap. Another similar trap 8^a 75 may be provided for covering the outlet between the lower and the upper members of the screen, said trap being of similar formation to the trap 8.

From the foregoing it will be obvious that a screen window or door provided with our 80 improvements will permit flies to gain an exit from the house and to be caught in traps through which they cannot regain an entrance to the house.

Our invention is of simple construction, 85 may be readily applied to any door or window screen and is very reliable and efficient for its purpose.

We claim:—

The herein described screen comprising a 90 frame having upper and lower cross bars connected by side bars, a lower reticulated member and an upper reticulated member spaced apart at their meeting edges, said upper member terminating below the upper 95 cross bar of the screen frame, a fly trap supported in the space between the upper edge of the last named member and said upper cross bar, the lower ends of the trap being spaced from the upper edge of said member 100 to permit flies to pass into said trap, and a removable fly trap adapted to be supported above the spaced apart edges of the reticulated members, substantially as described.

In testimony whereof we affix our signatures in presence of two witnesses.

WILLIAM FLANAGAN.
LOUIS MONROW MULLINIX.
